UNITED STATES PATENT OFFICE

100,105

DESIGN FOR A NAPKIN DISPENSER OR THE LIKE

Byron T. Hoffmaster, Appleton, Wis., assignor to Marathon Paper Mills Company, Rothschild,
Wis., a corporation of Wisconsin

Application March 19, 1936, Serial No. 61,691

Term of patent 14 years

To all whom it may concern:

Be it known that I, Byron T. Hoffmaster, a citizen of the United States, residing in Appleton, in the county of Outagamie and State of Wisconsin, have invented a new, original, and ornamental Design for a Napkin dispenser or the like, of which the following is a specification, reference being had to the accompanying drawing, forming a part thereof.

I claim:

The ornamental design for a napkin dispenser or the like, as shown and described.

In testimony whereof I affix my signature.

BYRON T. HOFFMASTER.
